UNITED STATES PATENT OFFICE.

JAMES EDGAR ROGERS, OF DANBURY, CONNECTICUT, ASSIGNOR OF ONE-THIRD TO
PAUL U. SUNDERLAND, OF DANBURY, CONNECTICUT.

ANTISKID DEVICE.

1,328,297.

Specification of Letters Patent. Patented Jan. 20, 1920.

Application filed March 15, 1919. Serial No. 282,942.

To all whom it may concern:

Be it known that I, JAMES EDGAR ROGERS, a citizen of the United States, residing at the city of Danbury, county of Fairfield, and 5 State of Connecticut, have invented certain new and useful Improvements in Antiskid Devices; and I do declare the following to be a full, clear, and exact description of the invention, such as will enable others skilled 10 in the art to which it appertains to make and use the same.

This invention relates to certain new and useful improvements in an antiskid attachment for wheels and its principal object is 15 to provide a simple attachment which may be expeditiously locked about a spoke and which will seat on the felly and be held thereon by the attached antiskid means.

The invention consists of an attaching 20 plate or body having chain attaching means at each end for securing a pair of circumferentially spaced antiskid chains about the tire, said body plate having a spoke-receiving recess and novel means for securing a spoke of the wheel therein in a quickly-detachable manner.

Further, the invention resides and consists in the features of construction herein-after more clearly described and claimed, 30 reference being had to the accompanying drawing wherein—

Figure 1 is a side elevation of the improved antiskid device as applied to a wheel, the latter being dotted in fragment.

Fig. 2 is a plan view thereof as seen from the plane indicated by line 2—2 of Fig. 1;

Fig. 3 is a top plan of the body plate *per se* with the locking gate or closure inoperatively disposed;

Fig. 4 is a bottom plan of the body plate; and

Fig. 5 is a section therethrough on line 5—5 of Fig. 3.

The body plate consists of a central portion 45 1 having attenuated ends 2 that are individually equipped with a pair of laterally disposed hooks 3 turned in opposing but spaced relation to permit the threading of the terminal links of an antiskid chain 4 thereover. Adjacent each end of the body plate is fixed the inner end of a leaf spring keeper 5 which has its outer end extending outwardly beneath and in contact with the adjacent turned and opposing hooks 3 to 50 bridge the intervening space and thereby act

as a guard for retaining both links on their own hooks. In this connection, it will be noted that the links are snapped into engagement merely by pressing the same down onto the spring keeper to depress the latter and then sliding the links laterally and in opposite directions beneath the hooks.

The central portion of the body plate is formed with a lateral cut-out or recess 6 for receiving a spoke of the wheel, and pivoted 65 at 7, to one side of the recess, is a closure or gate 8 designed to swing across said recess and close the same as well as to embrace the spoke. The gate 8 has a beveled outer end 9 to seat on a beveled face 10 on the opposite side of the recess where it is firmly secured by means of a catch 11 that is pivoted at 12 on the body plate and has a hook terminal 13 for engaging a pin 14 carried by the gate. The opposite terminal 15 of the catch lever 70 constitutes a handle and is normally held operative by a stop pin 16. This stop pin or latch operates in an opening through the body and is supported on an underlying leaf spring 17 that is fixed at one end to the underside of the body and has its opposite end 80 extending beyond the latter to constitute a handle. The leaf spring is guided within a groove 18 formed in the underside of the body.

In applying the antiskid device to a wheel, the body plate is passed about the selected spoke and the gate 8 swung to closed position where its pin 14 is engaged by swinging the catch lever 11. The stop pin 16 has 90 a side bevel to effect depression thereof as the lever rides over said bevel, and as soon as the lever is in its fully operative position it will have moved beyond the stop pin to permit the spring 17 returning the latter to operative position. To facilitate properly positioning the body plate and also to steady it from turning about the spoke, said body is provided with a pair of stops 19 which depend from the opposite 100 ends thereof to engage a side of the wheel felly. The chains may now be hooked to the ends of the plate.

To disconnect the device the chains are removed from about the tire and then by 105 pressing down on leaf spring 17 the stop or latch pin will be depressed from the path of the catch lever whereby it may be manipulated to release the gate.

Obviously, more than one device may be 110

applied to a single wheel and when a plurality are employed the spacing will be left to the judgment of the user. The stop pin 5 prevents accidental uncatching of the lever 11 when encountered by an obstruction on the road, and the spring keepers efficiently operate to hold the chains engaged with their hooks. The device also is quickly applied or removed without disturbing the 10 position of the wheel.

What is claimed is:

1. An antiskid attachment for wheels comprising a body plate adapted to seat on the wheel felly and formed with a central 15 lateral recess to receive a spoke, a gate pivoted to the body on one side of the recess to swing across the latter, a pin on the free end of the gate, a catch lever pivoted between its ends on the body and having a hooked 20 terminal to engage over the pin, a latch pin slidable through the body and into the path of the opposite end of the catch lever for holding it operative, a leaf spring secured to the bottom side of the plate in a guiding 25 groove formed therein and serving to hold the latch pin operative, and antiskid means carried by the body.

2. An antiskid attachment for wheels, comprising a body plate adapted to seat on the wheel felly and formed with a central 30 lateral recess to receive a spoke, a gate pivoted to the body on one side of the recess to swing across the latter, a pin on the free

end of the gate, a catch lever pivoted between its ends on the body and having a hooked 35 terminal to engage over the pin, a latch pin slidable through the body and into the path of the opposite end of the catch lever for holding it operative, a leaf spring secured to the bottom side of the plate in a guiding 40 groove formed therein and serving to hold the latch pin operative, and chain-securing means arranged at each end of the body.

3. An antiskid attachment for wheels, 45 comprising a body plate having a lateral, centrally located recess to receive a wheel spoke, means closing the recess to secure the spoke therein, depending stops at opposite ends of the body to engage a side of the 50 wheel felly, and means on the opposite ends of the body for connecting antiskid chains thereto.

4. An antiskid attachment for wheels, comprising a plate having a recess to embrace a wheel spoke, a gate pivoted to swing across the recess to close the same, a catch pivoted to the plate to engage the gate and hold it closed, and means for attaching an 55 antiskid chain to the plate. 60

In testimony whereof I affix my signature.

J. EDGAR ROGERS.
